UNITED STATES PATENT OFFICE.

OSCAR MAX KUCHS, OF ANACONDA, MONTANA, ASSIGNOR OF ONE-HALF TO FREDERICK LAIST, OF ANACONDA, MONTANA.

ORE-CLASSIFIER.

No. 927,059.

Specification of Letters Patent.

Patented July 6, 1909.

Application filed February 23, 1909. Serial No. 479,418.

To all whom it may concern:

Be it known that I, OSCAR MAX KUCHS, a citizen of the United States, residing at Anaconda, in the county of Deerlodge and State 5 of Montana, have invented certain new and useful Improvements in Ore-Classifiers, of which the following is a full, clear, and exact description, reference being had to the accompanying drawings, forming a part hereof.

10 My invention has relation to improvements in centrifugal slime classifiers; and it consists in the novel construction of classifier more fully set forth in the specification and pointed out in the claims.

15 In the drawings, Figure 1 is a combined vertical middle longitudinal section and part elevation of my invention; Fig. 2 is a vertical transverse section on the line 2—2 of Fig. 1; Fig. 3 is a vertical transverse section on the line 3—3 of Fig. 1; Fig. 4 is a detail section on the line 4—4 of Fig. 2 along the plane 20 of the securing flange of the hopper carried by the outer casing; and Fig. 5 is a sectional detail on the line 5—5 of Fig. 3 showing the 25 spacing block for the separated flanges of contiguous sections of the outer rotatable drum.

The present invention is particularly directed to the classification of the constituents of ore slimes, a by-product of the concentration of ores, composed of extremely small particles of respectively crystalline and amorphous or colloidal materials. The crystalline or sandy component is of course, derived from the wall rock and vein filling of the mine, the amorphous component resulting both from the weathering of the wall rock and vein filling, and from chemical decomposition of these same materials in the mill. The crystalline particles form the coarser constituent and are of sizes ranging up to 150 mesh, being composed chiefly of quartz, silicates, carbonates, oxids of metals, and the like, and metalliferous minerals, which carry the values to be extracted. The colloid or amorphous constituent is chiefly composed of clay, talc, hydrated silica, hydrated iron oxids, and in fact, any substance capable of existing in a colloidal state under 45 milling conditions. The diameters of these particles are in the neighborhood of .005 mm. The sand particles are perfectly independent of one another, being free to move without interfering with one another, where- 50 as the colloidal particles not only interfere

with each other but with the sandy particles as well; the crystalline material when thickened to a paste has the character of wetted sand, whereas the colloids under similar conditions resemble glue. The colloids tend to 60 remain in suspension in water indefinitely whereas the sands settle rapidly leaving a clear liquid above. Upon separation from the sands the colloids become flocculent. The addition of an electrolyte to the slime 65 or the application of heat has the effect of coagulating and precipitating the colloids as flakes which tend to settle rapidly, whereas the sands remain unaffected as long as their chemical structure is not attacked. Since 70 the colloids of the slimes tend to remain in suspension, it is obvious that they carry away with them considerable amount of the crystalline sands, in leaving the mill, any settling of these sands being out of question 75 as long as they remain associated with the colloids, and for this reason slime has heretofore eluded concentration.

It is the object therefore of my present invention to effect a centrifugal separation of 80 these slime components, at the same time grading the sandy particles thus separated and making them amenable to prevailing methods of concentration on tables, vanners and similar gravity concentrating machines. 85 The flocculent precipitate of the colloid constituent may be conducted to the tailings dump, or may be altogether ignored owing to the low values which it would generally 90 carry.

A further object of my invention is to construct a machine by which the slimes may be treated efficiently, economically and continuously, the classified sandy product or constituent being constantly discharged so 95 as to be constantly conducted by suitable launders to any available concentrating machine.

A further object is to construct a machine having a high capacity and yet entailing a 100 low cost of maintenance; one not necessitating frequent stops or repairs.

The advantages of my invention will be clearly apparent from a detailed description thereof which is as follows:

Referring to the drawings, B, represents an outer stationary casing of cast iron or steel, said casing being built up of a series of compartments or settling chambers separated by partition walls S, S', S'', S''' re- 110

spectively, each compartment being provided with a discharge hopper T , T' , T'' , or T''' , to the mouths of which are secured the hollow discharge plugs U , U' , U'' and U''' .
 5 Mounted centrally within the casing is an inner rotatable drum D to the heads or closed ends of which are secured the tubes or hollow trunnions F' , F'' , the tube F' being continuous with the feed pipe Z and with which it
 10 communicates through the medium of the stuffing box Z' . Secured to the trunnion F'' is a belt pulley N leading to a line shaft (not shown). The inner ends of the trunnions or tubes F' , F'' form supports for the terminal
 15 hubs or bearings J , J' of an outer drum C inclosing the inner drum and freely rotatable about the same. The hubs J , J' are provided with stuffing boxes K , K' of any well known and approved construction. The tube F''
 20 passes through a stuffing box R and bearing P' in the head of the casing B ; and at the feed end the tube F' passes through the extension a of the hub J , said extension or hollow shaft a passing through a stuffing-box Q
 25 and bearing P in the head of the casing B , and its terminal having keyed thereto a belt-pulley O of somewhat larger diameter than the pulley N , both pulleys being belted to pulleys of equal diameter on the line shaft
 30 (not shown), whereby the pulley O and hence the outer drum C which it rotates, will rotate at a lower rate of speed than the inner drum D .

The outer drum C is built up of sections, 35 two sections coming together within the compartments of the casing B , the planes of division between the sections passing through the mouths of the hoppers T , T' , T'' , T''' . The adjacent ends of two meeting sections of
 40 said outer drum are formed into pairs of converging flanges L , L' , L'' , L''' , the edges of the flanges being spaced apart by circumferential slits d which are continuous about the drum except at points where the flanges are
 45 secured together through the spacing blocks or formations M , (Fig. 5). These converging flanges L , L' , L'' , L''' thus form a series of circumferential pockets about the outer drum, said pockets having converging walls separated by discharge slits d . The outer drum is both longer, and of larger diameter than the inner drum D , the space between the peripheral and terminal walls of the two drums being formed into a series of channels
 50 c by a series of longitudinally and radially disposed wings or baffles 8 secured along the outer walls of the inner drum D and terminating at the inner ends of the tubes F' , F'' . The walls of the tubes F' , F'' , between the
 55 baffles are provided with openings $9'$, $9''$ respectively for the passage of the slime or pulp therethrough into and out of the channels c , said baffles serving to maintain the speed of rotation of the pulp and preventing
 60 any swirling.
 65

Disposed longitudinally with the casing B is a hydraulic water main V from which lead the branches, W , W' , W'' , W''' , into the respective compartments of the casing, each branch discharging water into its compartment opposite its corresponding discharge hopper T , T' , T'' , T''' . The casing is provided with feet Y , Y' , through which it is rigidly bolted to a timber foundation 10.

Mechanical details which may be illustrated but to which no reference is made are of common knowledge and hence are not entered into in the present description.

The operation of the classifier may be described as follows:—Rotation in a given and same direction is imparted to the drums C , D , through the belt-pulleys O , N , respectively, the inner drum revolving the faster and making approximately 80 revolutions to 79 revolutions of the outer drum. These drums of course, rotate about a common axis, and may be jointly considered as a centrifuge composed of two sections or drums spaced a suitable distance apart and rotating at different rates of speed. As the slime water or pulp is fed through the tube or trunnion F' it passes through the openings $9'$ thereof into the respective channels c between the baffles or deflectors 8 finally escaping through the openings $9''$ of the trunnion F'' into said trunnion, in the form of waste or colloid water as presently to be seen. During the rotation of the centrifuge (drums C , D) hydraulic water is constantly being discharged through the pipes W , W' , etc., into the respective compartments of the outer casing, which are kept full of water at a pressure slightly in excess of that exerted against the inner wall of the outer drum C as a result of the centrifugal action, so that there is a slight differential pressure exerted against the outer wall of the outer drum by the hydraulic water in the several compartments of the casing B . The result is that there will be a tendency for the hydraulic water to flow into the channels c between the drums through the slits d of the circumferential pockets formed by the flanges L , L' , etc. The slime water flowing through the channels c between the drums and baffles 8 is caught by the latter and made to rotate with the drums. In this combined longitudinal and rotary movement of the slime water the sands or concentrates settle out of it, being projected against the inner wall of the outer drum proper, and against the inner walls of the circumferential pockets formed by the converging flanges L , L' , etc., the coarsest sands which settle most rapidly being dropped near the feed end of the machine, the finest nearest the discharge end, and intermediate grades at points intermediate these two extremes. In this way there results a gradation in size of the sands deposited, each pocket being identified with a

specific grade of sands thus classified. The slime water by the time it reaches the openings 9" is freed of sands but is still charged with the colloid constituent of the slime, 5 which in the centrifugal treatment separates as a flocculent mass discharging with the water as waste.

The sands which settle against the inner wall of the outer drum between the pockets 10 would in time tend to form accretions which would materially interfere with the free flow of the slime water through the space between the drums, and thus interfere with the operation of the machine. By reason 15 however, of the differential in the speeds of rotation between the drums, the baffles 8 will constantly scrape the inner surface of the outer drum and thus prevent the formation of the accretions referred to. The sand is 20 thus loosened and carried along by the current traversing the channels *c*. Of course, the parts of the machine must be so proportioned and the width of the annular space between the drums must be such that the 25 velocity of the slime water passing through the channels *c* will sweep along all the precipitated sands and yet allow the finest sands to settle. The coarsest sands or those particles falling adjacent to the feed end of the 30 machine are rolled along or transported with the longitudinally moving current along the inner wall of the outer drum until they reach the pocket *L* into which they fall. In the same way the progressively finer sands are 35 carried along and fall into their respective pockets *L'*, *L''*, *L'''*, so that each pocket receives its specifically graded sand product. The sands thus precipitated into the several pockets now pass out of the centrifuge 40 through the slits *d* into the body of hydraulic water filling the outer casing *B*, or more properly speaking, the several compartments of said casing formed by the partition walls *S*, *S'*, *S''*, *S'''*. If the hydraulic water 45 pressure outside the centrifuge is great enough, water will be running into it through the slits *d*; and through this water the sands must pass or settle, on the same principle as falling particles of sand settle in a rising 50 water current in gravity classifiers. With the present arrangement, however, it will be seen that no water is thrown out by the rotating centrifuge at the periphery, and that sand alone is discharged, thus resulting in a 55 minimum loss of power in this direction. A part of this energy is utilized in that as the sands fly off tangentially they cause the water outside the centrifuge to rotate with it, thus reducing the friction between the 60 water and the drum *C*. The sands having passed out of the slits *d* into the water of the outer casing *B* settle into the respective hoppers *T*, *T'*, etc., and are discharged through the open plugs *U*, *U'*, etc., whence, graded 65 in the manner described they are delivered

into launders 3, 3, and conducted to any suitable gravity concentrators.

From the foregoing, it is apparent that there must necessarily result three final classes of material, viz., (a) waste colloids 70 or centrifugal tailings, discharged from the discharge-trunnion *F* of the machine with water from which the sands have separated; (b) table tailings which result from the concentration of the classified sands; and (c) 75 concentrates resulting from the concentration of the classified sands. Obviously the machine need not necessarily be restricted to the classification of slimes, but may treat any ore pulp susceptible of classification and 80 concentration.

It may be stated in passing that the discharge through the slits *d* into the settling chambers of the casing *B* being in planes parallel to the plane of rotation of the 85 centrifuge, and at right angles to the axis of the drums contributes to reduce the friction between the outer drum and the water in the casing *B*.

Having described my invention, what I 90 claim is:—

1. In a classifier, a centrifuge comprising a pair of concentric drums spaced a suitable distance apart, means for rotating the same at different speeds, means for conducting the 95 pulp in individual currents through said space from one end of the centrifuge to the opposite end, the walls of the outer drum being provided with pockets having slits for the discharge of the classified material, said 100 pockets being disposed along the path of travel of the individual currents aforesaid, and an outer casing for receiving the material discharged through the slits of the 105 pockets aforesaid.

2. In a classifier, a centrifuge comprising a pair of concentric drums spaced a suitable distance apart, means for imparting to the inner drum a speed of rotation slightly in excess of that of the outer drum, means for conducting the pulp in individual currents through said space from one end of the centrifuge to the opposite end, the walls of the outer drum being provided with pockets having openings for the discharge of the 110 classified material, said pockets being disposed along the path of travel of the individual currents aforesaid, and an outer casing for receiving the material discharged 115 from the pockets.

3. In a classifier, a centrifuge comprising a pair of concentric drums spaced a suitable distance apart, means for imparting to the inner drum a speed of rotation slightly in excess of that of the outer drum, a series of 120 baffles disposed longitudinally of the drums carried by the outer wall of the inner drum, the walls of the outer drum being provided with pockets having slits for the discharge of the 125 classified material, said pockets being 130

disposed along the path of travel of the currents between the baffles, and an outer casing for receiving the discharges from the pockets of the outer drum, said casing being provided with a discharge mouth.

4. In a classifier, a centrifuge comprising a pair of concentric drums rotatable about a common axis, and spaced a suitable distance apart, means for conducting the pulp in 10 individual currents through said space from one end of the centrifuge to the opposite end, the walls of the outer drum being provided at points between the ends of the centrifuge with pockets having discharge openings, the 15 currents aforesaid flowing past said pockets, and an outer casing for receiving the material discharged from the pockets.

5. In a classifier, a centrifuge comprising a pair of concentric drums rotatable about a 20 common axis, and spaced a suitable distance apart, means for conducting the pulp through said space from one end of the centrifuge to the opposite end, the walls of the outer drum being provided at points between the ends 25 of the centrifuge with pockets having discharge openings, the currents aforesaid flowing past said pockets, an outer casing for receiving the material discharged from the pockets, and means for maintaining in the

outer casing a pressure slightly in excess of 30 and in opposition to the centrifugal force developed in the rotation of the centrifuge.

6. A classifier comprising a centrifuge composed of a pair of rotatable concentric drums spaced a suitable distance apart, a 35 series of baffles disposed longitudinally of the drums carried by the outer wall of the inner drum, a series of circumferential pockets being formed on the outer drum and terminating in slits for the discharge of the 40 classified material, an outer stationary casing supporting the drum and provided with compartments encompassing the outer drum and receiving the discharges from the slits aforesaid, a discharge mouth being provided for 45 each compartment, and water feed pipes leading into the several compartments and discharging hydraulic water thereinto slightly in excess of and in opposition to the centrifugal force developed in the rotation of 50 the drums.

In testimony whereof I affix my signature, in presence of two witnesses.

OSCAR MAX KUCHS.
